UNITED STATES PATENT OFFICE.

THEODORE WILLARD CASE, OF AUBURN, NEW YORK, ASSIGNOR TO CASE RESEARCH LABORATORY INCORPORATED, OF AUBURN, NEW YORK, A CORPORATION OF NEW YORK.

METHOD AND APPARATUS FOR TRANSLATING OR TRANSMITTING SOUND WAVES.

Application filed October 7, 1922. Serial No. 593,110.

This invention relates to a certain new and novel method and apparatus for translating or transmitting sound waves.

Attempts have been made to impress voice variations upon an electric arc, but so far as I am aware, no one has been able to produce an effective apparatus of that character, for the reason that the arc is of such variable intensity and the temperature of the gases is so changeable, that it has been impossible to maintain a constant stability essential to commercial translation or transmission. For that reason reproduction, even at short distances, has been irregular, inaccurate and uncertain.

15 The essentials of my invention are, therefore, the combination with a source of light of high intensity, constant value and of the proper form and size for the purpose at hand, of means for varying such light in accordance with variations in sound waves, as for instance, the impression of sound waves upon one of the combustible fluids entering into the light.

Another object relates to the combination 25 with an apparatus such as that referred to in the former paragraph of a photographic film upon which the variations in sound waves as translated in waves of light may be photographed or reproduced.

30 My invention is, therefore, adapted for many uses, and other objects relate to the details of form, construction and arrangement and its combination with various devices, all as will more fully appear from the following 35 description, taken in connection with the accompanying drawings, in which:—

Figure 1 is a diagrammatic illustration of an apparatus of my invention.

40 Figure 2 is a diagrammatic illustration of a varied form of my invention embodying amplifying means.

Figure 3 is a diagrammatic illustration of a further embodiment of my invention.

45 Generally speaking, the apparatus of Figure 1 embodies a burner —1— upon which voice variations may be impressed. Such burner may be enclosed in a suitable housing —2— embodying a reflector —3— for directing the light waves or rays in the manner desired, and this housing may be closed at its front end by a transparent plate —4— of glass or the like.

For the purpose of receiving and translating such light waves into signals or sound

waves, various apparatus may be used the one 55 shown in Figure 1 consisting of a cell —5— embodying a light reactive material or a resistance of some character that varies in accordance with the intensity of the light rays to which it is subjected. Such cell may be 60 positioned in front of a reflector —6— concentrating the rays upon the cell. This cell is connected in circuit and forms a portion of the circuit which includes a battery —7— and a translating device, such as the telephone receivers —8—.

The operation of this apparatus will be understood. The variations in the flame produced at the burner —1— will cause similar variations in the resistance of the cell —5—, thereby varying the current flowing in the circuit containing the battery —7— and the receivers —8— so that said current will pulsate in the circuit at a frequency determined by the variations in the flame at the burner, thereby 75 reproducing the sound waves impressed upon the burner.

A perhaps preferred embodiment of my receiving apparatus is disclosed in Figure 2, in which a thermo-electric cell —35—, including 80 a light reactive material positioned near the path of the thermo-electric current and which varies its electron emission in substantial accordance with the intensity of the light rays to which it is exposed all as described in my 85 co-pending application Serial No. 523,603 filed Dec. 19, 1921. The light reactive material should be adjacent the thermo electric current and may, as illustrated, be coated on a portion of the inner surface of the vacuum 90 bulb. The cell —35— is connected in circuit across the filament —10— and the grid —11— of the audion —9—, such circuit including preferably a variable source of potential —12—. The filament —36— may be connected to the grid —11— while plate or electrode —38— is connected to the filament —10— of the audion.

The filament 10 is connected in circuit with the plate —13— such circuit including a battery, and if desired, a suitable translating device such as telephone receivers. The filament or electrode —36— may be heated in any suitable way, as by battery —37—. In this particular illustration, a two-step amplification is effected by including in the circuit between the filament —10— and plate —13— the primary —14— of a transformer, the sec-

ondary —39— of which is connected across the filament —15— and grid —16— of a second audion —17—, the plate of which is connected to the filament across battery —18— 5 and a translating device, such as the telephone receiver —19—.

By this construction of apparatus, a material amplification of pulsating current of the device of Figure 1 and various stages or 10 audion steps may be utilized in a device of this character.

The essentially novel arrangement is not, however, restricted to any particular circuits or any particular steps of amplification. An 15 important portion of my invention resides in the transmitting or sending apparatus alone, and this apparatus includes the burner —1— which is of a peculiar construction, particularly when combined with a means for varying 20 the flame of said burner in accordance with sound waves. This transmitting apparatus of my invention, so far as I am aware, produces for the first time a satisfactory flame of high intensity and constant value, 25 rendering the apparatus capable of effecting sensitive results when utilized in connection with a receiving or translating apparatus.

This sending apparatus comprises an acetylene burner —20— suitably connected to 30 an acetylene tank —21— as by a flexible conduit —22— which may be provided with a suitable valve —40— for controlling the flow of the combustible fluid. The conduit —22— preferably has a branch —23— terminating 35 in an enlarged preferably cone-shaped part —24— constituting a mouth piece closed at its end by a diaphragm —25— of suitable material. Any suitable diaphragm may be utilized, and I have used one formed of prepared paper tightly stretched across the mouthpiece and secured in position in any suitable way.

Sound waves striking the diaphragm vary 40 the pressure of the fluid in the conduit —22— and thereby vary the intensity of the flame produced in the burner. I am, therefore, enabled to vary the flame in accordance with articulate sound waves.

It is found that the ordinary acetylene 45 flame is of little value for the purpose of this invention, and that an oxy-acetylene flame when the oxygen is introduced in the conduit —22— is likewise of little practical value. I have, however, discovered that a 50 flame of the desired high intensity and constant value can be produced by introducing oxygen directly into the acetylene flame. Preferably, this is effected by directing two 55 upwardly inclined streams of oxygen toward each other from opposite sides of the acetylene burner, and fixed nozzles —24— and —25— are indicated for this purpose, and 60 may be connected by a single conduit —26— to a tank —27— adapted to contain oxygen under pressure. The conduit —26— may

contain a suitable valve —28— for controlling such communication.

By this burner a flame of substantially constant value and high intensity, and of the desired shape, spread and size may be produced, and such a flame is peculiarly adapted for the translation and transmission of sound waves by reason of its high intensity and constant value.

In Figure 3 I have diagrammatically illustrated a modified form of burner as assembled with a photographing means for photographing variations in the burner flame produced by variations in articulate sound waves, altho the burner of Fig. 1 may be utilized and is in itself sufficient. This burner in addition to the mouthpiece —24'— and diaphragm —25'— in the acetylene line —22— includes a mouthpiece —42—, diaphragm —43— in the branch —44— of the oxygen line —26— 75 for varying the pressure of the oxygen supplied to the burner in accordance with sound waves and with this arrangement, the mouthpiece —24'— and diaphragm may be conjointly used or either may be omitted, if desired, the only requirement being that the sound waves be impressed upon one of the combustible gases supplied to the burner. This apparatus may include a suitable lens —30— and a suitable film —31— combined 80 with the usual and ordinary means for moving the film across the aperture through which the light waves are admitted after passing through the double convex or concentrating lens —30— to the film space.

By this apparatus there may be produced upon a film a photograph of the varying flame at the burner, which photograph may, in connection with a source of light and a translating apparatus embodying a light reactive cell, be utilized for reproducing the articulate sound waves which originally effected the variations in the photographed flame.

It will be obvious that this sound transmitting and translating apparatus is capable 105 of use in many and various assemblages and for many and various purposes, and I do not desire to limit myself to any particular independent translation or to any particular receiving apparatus.

I claim:

1. In an apparatus of the class described, a primary burner a source of combustible fluid under pressure having means of communication with the burner, means adapted to be operated by sound waves for varying the pressure of the fluid as supplied to the burner, a source of oxygen under pressure and means for directing a stream of oxygen into a flame at the burner.

2. In an apparatus of the class described, a burner, means for supplying combustible fluid to the burner, means for varying the pressure of the fluid supplied to the burner in accordance with sound waves, a source of

oxygen under pressure and means for directing a stream of oxygen into a flame at the burner.

3. A light wave transmitting apparatus comprising a burner including tubes for discharge of acetylene gas and oxygen gas, means for supplying said gases to their respective tubes, and means for varying the pressure of one of said gases in accordance with sound waves.

4. The method of varying a flame in accordance with sound waves comprising producing a flame by ignition of a combustible gas and varying the pressure of the gas supplied to said flame in accordance with sound waves, and introducing a second gas under pressure into said flame.

5. The method of varying a flame in accordance with sound waves comprising producing a flame by ignition of a combustible gas and varying the pressure of the gas supplied to said flame in accordance with sound waves, introducing a second gas under pressure into said flame.

sure into said flame, and varying the pressure of the second gas in accordance with the same sound waves.

6. In sound recording apparatus, a sound controlled actinic flame device comprising; a burner having independent supply connections for oxygen and combustible gas; and an acoustic diaphragm in contact with the combustible gas supply adjacent the burner whereby the visible length of the flame may be modulated by sound waves.

7. In sound recording apparatus, a sound controlled actinic flame device comprising a burner having independent supply connections for oxygen and combustible gas, and an acoustic diaphragm in contact with the combustible gas supply adjacent the burner whereby the visible length of the flame may be modulated by sound waves, and photographing upon a film the flame as varied.

In witness whereof I have hereunto set my hand this 29th day of September 1922.

THEODORE WILLARD CASE.
